UNITED STATES PATENT OFFICE.

SOLOMON H. GODMAN, OF INDIANAPOLIS, INDIANA.

BRIDGE.

SPECIFICATION forming part of Letters Patent No. 349,345, dated September 21, 1886.

Application filed June 12, 1885. Serial No. 168,456. (No model.)

To all whom it may concern:

Be it known that I, SOLOMON H. GODMAN, of the city of Indianapolis, county of Marion, and State of Indiana, have invented certain 5 new and useful Improvements in Bridges, of which the following is a specification.

As is well known to those familiar with the art of bridge-building, the scarcity of stone in certain localities and its consequent high price 10 has created a demand for a substitute therefor in the construction of the substructures of bridges. Iron pillars have been used as a substitute, but owing to faulty arrangement and connection to the bridge have failed to satisfactorily perform the functions of a firm, steady, 15 and durable structure, and necessitates the building of wooden approaches to the bridge, which are neither slight nor durable.

My said invention consists, therefore, in the 20 construction and arrangement of a substructure and its connection to the bridge, whereby the above disadvantages are avoided, and a strong, durable, and firm structure produced, and a solid earth approach provided for, as 25 will be hereinafter more fully described.

Referring to the accompanying drawings, which are made a part hereof, and on which similar letters of reference indicate similar parts, Figure 1 is a side elevation of a bridge 30 embodying my said invention; Fig. 2, an under side view, looking upwardly from the dotted line 2 2; Fig. 3, a transverse vertical sectional view, on an enlarged scale, looking to the left from the dotted line 3 3, showing the sub- 35 structure in front elevation; and Fig. 4, a detail sectional view as seen from the dotted line 4 4.

In said drawings, the portions marked A represent the girders of the bridge; B, the sills 40 of the substructure; C C', the posts of the sub-structure; D, cross-beams connecting the several posts; E, braces extending from the posts C to the girders, and F planking to support the earth in position.

The girders A are preferably built up of 45 metal plates and angle-irons, as is common in such places; but of course may be of any other suitable construction preferred. Their ends rest on the tops of the posts C, as shown, and 50 are secured thereto by angle-irons and bolts, or in any suitable manner. The roadway is completed by the use of floor-beams A', joists

or stringers A², and planking A³, suitable for the purpose, the floor-beams being stayed by brace-rods a' in the usual and well-known manner. 55

The sills B are preferably timbers; but of course may be of iron or stone, if desired. They are embedded in the earth directly under the points where the ends of the bridge will 60 come, preferably below low-water mark.

The posts C are preferably heavy wrought-iron posts of sufficient size to support the superstructure steadily. They are securely fastened to the sills at their lower ends, generally 65 by means of angle-irons, and have the ends of the girders secured to their tops, as before described. They are preferably in the form of I-beams, and the braces E are secured thereto by means of rivets or bolts passing through 70 their flanges and similar flanges formed on the braces, as shown. The posts C' are similar to the posts C, except that they are the thickness of the cross-beam D shorter. They are also secured to the sills B in a similar manner, 75 and at their upper ends are firmly secured to the cross-beams D.

The cross-beams D are of suitable size and strength to afford a rigid lateral support or stay to the posts C, which they tie together by 80 being firmly secured to the tops thereof at their ends, as shown, and a similar stay for the posts C', which are secured thereto as above stated, in addition to supporting the ends of the floor-timbers, as before described. 85

The braces E are preferably built up from metal plates and angle-irons similarly to the girders. They are secured to the girders A by rivets or bolts e, and to the main posts C by rivets or bolts e', as shown and before described. Instead of the plain form of brace shown, it may be made in the form of a low arch, as will be readily understood. Said brace or arch is so arranged as to bring the thrust thereof directly opposite the pressure of 90 the earth from the outside, and the posts are thereby held rigidly in position, being thus firmly supported from each side. 95

The walls F are preferably of plank; but may be of metal plates, if desired. The lower 100 edges rest upon the sills B, behind the foot of the posts, and are built up to the top of said posts, closing the open spaces between them, thus preventing any of the earth fill from pass-

ing through, and bringing the entire pressure thereof directly against the rear side of said posts, thereby counteracting the thrust of the braces or arches against the front side of the 5 posts.

The entire bridge, when completed, is practically in one piece, the several parts being secured firmly together, and a rigid and solid structure is thus produced, the several parts 10 of which each operate to brace and support the others, and add strength and solidity thereto. This construction permits a solid earth roadway to be built directly to the bridge, avoiding the necessity of a wooden approach.

Having thus fully described my said invention, what I claim as new, and desire to secure by Letters Patent, is—

1. The combination, in a bridge, of the girders A, posts C, braces E, arranged between 20 said posts and girders, and the wall F, arranged behind said posts, against which the earth fill bears, substantially as set forth.

2. The combination of the sills B, the posts

C and C', mounted on said sills, the cross-beam D, secured to the tops of said posts, the girders 25 A, supported on said posts, the braces E, running between said posts C and said girders, and the wall F, behind said posts, substantially as set forth.

3. The combination of the girders of a bridge, 30 posts supporting said girders, braces or arches running from said posts to said girders and secured to each, a wall behind said girders, and a fill between said wall and the bank of the stream, which bears against said wall, whereby 35 the thrust of the brace or arch against the opposite side of said posts is counteracted and a solid structure produced, substantially as set forth.

In witness whereof I have hereunto set my hand and seal, at Indianapolis, Indiana, this 9th day of May, A. D. 1885.

SOLOMON H. GODMAN. [U. S.]

In presence of—

C. BRADFORD,

E. W. BRADFORD.
